UNITED STATES PATENT OFFICE.

CHARLES H. DEMPSEY AND THOMAS F. BARNES, OF LOS ANGELES, CALIFORNIA.

CASE-TABLE.

1.256,211.

Specification of Letters Patent. Patented Feb. 12, 1918.

Application filed June 28, 1915. Serial No. 36,571.

To all whom it may concern:

Be it known that we, CHARLES H. DEMPSEY and THOMAS F. BARNES, both citizens of the United States, residing at Los Angeles, in the county of Los Angeles and State of California, have invented a new and useful Case-Table, of which the following is a specification.

An object of this invention is to provide 10 novel and convenient means for alternately or alternatively storing and displaying and making available articles desired to be stored at one time and to be displayed or made available for use at another time.

15 This invention is more particularly intended for use as a lunch box, basket or hamper in combination with a table to afford special convenience for campers and picnickers, but the invention may also be 20 found very desirable for use as a ladies' combination work-box and table; and also as a convenience for dealers in notions and other wares which are to be carried from place to place and exhibited or displayed 25 for inspection or for sale on the streets or at other places temporarily used for such exhibition, display, inspection or sale.

The invention is regarded as broadly new and pioneer in that a box is constructed to 30 serve as a container for the articles to be stored, transported and displayed, and in combination with said box there is applied a table top of convenient form and construction, which may be adjusted at one 35 time to serve as a closure for the box and at another time as a support for the one-time contents of the box; said table top and box closure combined, being preferably connected to the container by collapsible and 40 extensible means such as lazy tongs, toggle-joints, legs or other devices which will support the table top in an elevated position above the container and which can be collapsed when it is desired to close the box.

45 Another novel feature of the invention in its preferred form is the provision of means whereby the contents of the box may be made available without raising the table top to its elevated position; and a special object 50 of convenience in this respect is the enabling of the attendant to unpack the box and place its one-time contents on extended horizontal portions of the table top while the table top is practically at the level of 55 the top of the container.

The invention may be carried out in various ways and we do not limit the same to

the particular features of construction, although the invention includes the combination case table and the various novel parts 60 and combinations of parts going to make up the same.

The accompanying drawings illustrate the invention in a preferred form.

Figure 1 is a side elevation of the combination case table in the form at present deemed most desirable, the case being open and the parts being in position for using the device as a display or dining table.

Fig. 2 is an end elevation of the device 70 shown in Fig. 1 when closed.

Fig. 3 is a mid-section on line x^3 , Fig. 2.

Fig. 4 is a cross sectional elevation on line x^4 , Fig. 1.

Fig. 5 is a plan of the device shown in 75 the preceding views one of the slides of the table top being drawn out to give access to the interior of the container, and the other slide being withdrawn to expose the tie or brace of the legs. The removed slide is 80 turned upside down.

The container 1 may be of any suitable form and is shown as a rectangular wooden box. To said box there are hinged four leg sections 2, corresponding to each other 85 and connected to the box by pivots 3 seated in the side walls 4 of the box about midway of the length of the box. Said leg sections are foldable into the box and are adapted to be drawn into upright position to rest 90 against the end walls 5 of the box; and for the purposes of stability said leg sections are bent outward to overhang the end walls 5 when the leg sections are in upright position and contacting with said walls. With 95 this object in view the lower leg sections are constructed in two limbs viz.: the straight lower limb a , and the oblique upper limb, b ; the upper limbs b overhang the end walls 5 when the leg members are extended to support the table top in elevated position, the upper member $2'$ of each of said legs comprises a lower bent limb c , and an upper straight limb d , the general effect of the two members being complementary to each 105 other so that the upper limb d of the upper member overhangs the inside of the box, said upper limb b of the lower member and lower limb c of the upper member $2'$ are hinged together by hinge 6, and the abutting 110 ends of the members 2 and 2' constitute stops for each other to prevent the legs from collapsing except when the hinges 6 are pushed inward, said hinges 6 being

mounted on the outer or box-end overhanging faces *e* of the legs.

A pair of legs is thus pivotally mounted at each end of the container.

The upper ends of the legs are pivotally connected by pivots *7* to side rails *8* of the table top or closure for the container, and connecting ties *9* underneath the table top give rigidity to the legs against lateral displacement; there being a tie for each pair of legs.

Said tie *9* is preferably connected to and moves with its legs, and with the pivots *7* connects not only the legs but also the table top rails *8* at the ends of the box.

The table top comprises three sections, the central section being a skeleton frame comprising guides *10* extending along the box, and connecting means *11* in the form of a bar connecting the guides *10*. Said guides *10* are so spaced apart that their outer edges are flush with the outer faces of the side walls *4* of the box. The side rails *8* are connected to the guides and are connected together by the pivots *7* and cross bars *9*.

The cross ties are angular in cross section and are hollowed out on their inner faces to lighten the bars; each cross tie having a flat side *f* and a rounded portion *g*, said sides adjoining each other and arranged to be alternately turned to form an end wall of the closure above the end wall of the container; the rounded portion of said cross tie being adapted to fit close to the under side of the closure when the closure is closed, and to allow rotation of said cross tie on the pivots *7*.

The flat face *f* is exposed at the end of the closure or table top when the table top is elevated as shown in Fig. 1, and is flush with the outer face of the end wall when the table top is raised.

Said closure or table top is provided between the ways *10* with slides *12* provided with the hand holds *13* and the tongues *14* so that they may be grasped and slid out and in to open or to close the container when the frame of the closure is in closing position.

For security the side walls are provided with stops *15* against which the lower members *2* of the legs come to rest when the closure is down, and latches *16* engage in slots *17* in the members *2* to hold said members in rigid relation to the ends of the box when the legs are extended.

The members *2* and *2'* with hinges *6* constitute toggle joints allowing the hinges *6* to pass dead center in the operation of erecting the legs, thus to give a measure of stability to the table when it is drawn up. By turning the latches *16* to enter the slots *17* in the lower leg members *2*, the legs are so locked as to remain rigid until the latch is released and pressure is applied inwardly

against the hinges *6* to collapse the legs and allow them to fold down into the box.

Handles *18* on the end walls of the container afford convenience for carrying the device.

Folding leaves *19* are connected by hinges *20* to the guides *10* of the closure and constitute the folding sections thereof, and the rails *8* are provided with props *21* pivoted at *22* to the rails and supported by the middle cross bar *11*, that serves as a purchase for the props when the leaves are raised, thus to support the leaves after the manner of the leaves of an ordinary leaf table. Fastening means *23* in the form of hooks *80* and eyes are provided to connect the leaves *19* with the container, said hooks being fastened to the end walls *5* and the eyes to the table leaves in position to be brought into engagement with each other when the leaves *85* are folded.

In practical use when the container is closed by the closure as indicated in Figs. 2 and 3, the leaves can be raised as indicated in Fig. 4 and this can be done without lifting the closure from the container. Then the slides *12* may be drawn out, thus giving access to the interior of the container so that the contents may be removed from the container and placed on the table leaves, *95* and they may also be placed on the slides partly drawn out as at *12* at the right of Fig. 5.

When the table has thus been set, the slides may be pushed back into place, and then the attendant will lift up the closure thus bringing it into the position shown in Figs. 1 and 4, when the device will be ready for use as a dining table.

If preferred in picnicking, to eat off of *105* the table without bringing it to its elevated position, that can be readily done while the closure is in closed position.

When the table top has been elevated as in Fig. 1 the latches will be drawn into place *110* by the attendant, thus holding the legs rigidly.

By unlatching the latches and pushing inward on the hinge joints at the hinges *6* the legs will be collapsed and the closure returned to its closed position, then if it is desired to return to the container the objects supported by the table top, the slides may be drawn out thus opening the container to receive the articles, which may be placed *120* therein and the slides closed thus shutting the box.

We claim:

1. A container; a closure for the container; and means at the ends of the container and at the ends of the closure for connecting the closure and the container, said means consisting of toggle-joints which are at their lower ends pivotally supported within the container at a short distance from the *130*

bottom thereof, and said toggle-joints being adapted to pass beyond their dead centers and when so passed to support the closure above the container, and when collapsed to 5 allow the closure to close the container.

2. A container; a closure for the container; and legs pivotally connected within and to the container at the ends thereof and at a short distance from the bottom of 10 the container, and to the closure at the ends of the closure, said legs being adapted to move inwardly and away from said ends in order to allow the closure to close the container.

15 3. A container; a closure for the container; and collapsible legs pivotally connected within and to the container at the ends thereof and at a short distance from the bottom of the container, and to the closure 20 at the ends of the closure, said legs being movable inwardly and away from said ends for holding the closure closed upon the container.

4. A container; a closure for the container; and collapsible legs pivotally connected within and to the container at the ends thereof and at a short distance from the bottom of the container, and to the closure 25 at the ends of the closure, said legs being movable toward said ends in order to support the closure at one time, and movable inwardly and away from the ends at another time in order to allow the closure to close the container.

35 5. A container; a closure for the container; legs constructed in two parts, each of said parts having a bend therein; and said parts being respectively pivoted within and to the container at the ends thereof and 40 at a short distance from the bottom of the container, and to the closure at the ends of the closure, said parts being collapsible in order to allow the closure alternately to close the container or to be supported there- 45 above by said legs.

6. The combination with a container open at the top; of a closure for said container; said closure comprising a table top, and side rails for said table top; legs constructed in 50 two parts, each of said parts having a bend therein and being provided at the top with a cross tie connecting the two legs; means pivoting the parts respectively to the rails at the ends thereof; and means pivotally 55 connecting the legs to the container; said legs being collapsible and extensible to alternately allow the closure to close the container and to support the closure above the container.

60 7. The combination with a container open at the top; of a closure for said container; said closure comprising a table top, and side rails for said table top; legs constructed in two parts, each of said parts having a bend 65 therein and being provided at the top with

a cross tie connecting the two legs; means pivoting the parts respectively to the rails at the ends thereof; means pivotally connecting the legs to the container, said legs being collapsible and extensible to alternately allow the closure to close the container and to support the closure above the container; and means to latch the legs in closure-supporting position. 70

8. The combination with a container having side walls and end walls, of a closure for the top of the container, lower leg sections pivotally connected to the container inside the same at the ends thereof, upper leg sections pivotally connected to the 75 closure at the ends thereof, hinges connecting the lower and upper leg sections together at one end of the container and closure, hinges connecting the lower and upper leg sections together at the other end of the 80 container and closure, and means to hold the leg sections rigid when extended. 85

9. A container having side and end walls, a closure for the top of the container, lower leg sections pivoted to the container at the 90 ends thereof and overhanging the end walls, hinges connected to the outer overhanging edges of the lower leg sections, upper leg sections connected to the lower leg sections by said hinges and overhanging said lower 95 leg sections, and means pivotally connecting the closure to the upper ends of the upper leg sections.

10. A container having side and end walls, a closure for the top of the container, lower 100 leg sections pivoted to the container at the ends thereof and overhanging the end walls, hinges connected to the outer overhanging edges of the lower leg sections, upper leg sections connected to the lower leg sections 105 by said hinges and overhanging said lower leg sections, means pivotally connecting the closure to the upper ends of the upper leg sections, and means for holding the leg sections in rigid relation to the container 110 when the legs are extended.

11. A container open at the top, a closure for the top of the container, leaves connected to the closure and adapted to fold against the sides of the container and to be extended 115 away therefrom on a level with the closure, and means to support the leaves in the extended position.

12. A container, a closure for the container, leaves in hinged relation to the 120 closure and foldable against the sides of the container, and means to support the leaves in horizontal position; the closure being provided with one or more slides to give access to the interior of the container while the closure is in container-closing position.

13. A container, a closure for the container, leaves hinged to the closure and foldable against the sides of the container; and means to hold the leaves in horizontal posi- 130

tion, said closure being provided with a cross bar and sliding means above the top opening of the container, said cross bar serving as a purchase for the leaf-holding means; and said slides abutting against said cross bar when closed and adapted to be opened to give access to the interior of the container while the leaves are in horizontal position.

- 10 14. A container having side walls and also having end walls that terminate below the level of the tops of the side walls; a closure constructed with stiles above said side walls with a cross bar connecting said stiles and 15 with rails above the side walls of the container; said stiles being grooved on their inner edges; and slides working in said grooves to temporarily close the container and to give access to the interior thereof.
- 20 15. A container having side walls and end walls and being open at the top; a closure

for the top of the container; stops fastened to the inside of the side walls of the container; lower leg sections pivoted to the side walls of the container and adapted to rest 25 on the stops; means to hold the lower leg sections erect; upper leg sections hinged to the upper ends of the lower leg sections; a tie connecting together the upper ends of the upper leg sections at one end of the container; a tie connecting the upper ends of the upper leg sections at the other end of the container; and means connecting the ties to the closure.

In testimony whereof, we have hereunto 35 set our hands at Los Angeles, California, this 19th day of June, 1915.

CHARLES H. DEMPSEY.
THOMAS F. BARNES.
